UNITED STATES PATENT OFFICE

ARNOLD R. RASMUSSEN, OF SHARON, NORTH DAKOTA

ART OF HANGING CLOTHES

Application filed May 28, 1931. Serial No. 540,750.

This invention relates to new and useful improvements in the art of hanging clothes to dry and has for its primary object to provide, in a manner as hereinafter set forth, a clothes holder embodying a novel construction and arrangement of parts for securing the clothes detachably to a clothes line.

Another important object of the invention is to provide a clothes line and clothes holder for detachable mounting on the line, said line and clothes holder embodying co-acting means for preventing longitudinal movement of the holder relative to the line.

Other objects of the invention are to provide a structure of the aforementioned character which will be simple in construction, strong, durable, efficient and reliable in use, and which may be manufactured at low cost.

All of the foregoing and still further objects and advantages of the invention will become apparent from a study of the following specifications, taken in connection with the accompanying drawing wherein like characters of reference designate corresponding parts throughout the several views, and wherein:

Figure 1 is a view in front elevation of a device in accordance with this invention.

Figure 2 is a view in rear elevation thereof.

Figure 3 is a view in side elevation of the device.

Referring now to the drawing in detail, it will be seen that the reference numeral 1 designates a bar of any suitable material, preferably wood, and having an inclined or beveled upper end portion 2. Extending around the bar 1 adjacent the upper end thereof is a groove 3 and said bar is further provided, on its rear or back, with a transverse channel 4 which is spaced below the groove 3. The bar 1 is still further provided, on its upper end portion and on its back with the longitudinally extending grooves 5 which extend upwardly from the channel 4 and across the bevel or inclined upper end portion 2, said grooves 5 intersecting the groove 3.

Mounted on the bar 1 and formed integrally with each other is a line engaging supporting hook designated generally by the reference

numeral 7 and a clothes clamp which is designated generally by the reference numeral 8. The hook and the clamp 8 are formed from a single piece of resilient wire which is bent at an intermediate point upon itself, as at 9, 55 the side portions of the bent wire extending in spaced parallelism with each other for a portion of their length. The hook 7 comprises the upwardly and downwardly disposed spaced, parallel portions 10 and an outwardly curved free end portion 11. The wire is further bent to provide the spaced, parallel, diagonal portions 12 which merge with the portions 10 of the hook 7, said portions 12 being disposed or seated in the grooves in 60 the beveled end portion 2 of the bar 1.

The wire is still further bent to provide the spaced, parallel portions 13 which are seated in the grooves 5 which are provided in the body portion of the bar 1. The portions 13 70 are convoluted in opposite directions to provide the springs 14 which are seated in the transverse channel 4 in the bar 1. The outer ends of the springs 14 merge with the downwardly directed legs 15 of the clamp 8. The lower portions of the legs 15 of the clamp 8 extend at an angle, as at 16. The wire, from the legs 15, and the portions 16, is then bent upwardly and forwardly, as at 17, and then upwardly and rearwardly as at 18. At its 75 ends, the wire terminates in inturned end portions 19 which are disposed within and secured together by a tubular sleeve 20 which is adapted for engagement in the transverse channel 21 provided therefor in the lower end 80 portion of the front of the bar 1.

A staple 22 is clinched around the bar 1 in the groove 3 and extends across the portions 13 of the wire for securing the hook and the clamp in position on the bar 1. A plate 23 90 extends between the leg portions 15 of the clamp 8 and has its end portions looped around said leg portions for mounting the plate on the clamp.

The clothes line is designated by the reference numeral 24 and is provided, at spaced points, with enlargements, only one of which is shown in the drawing, the same being designated by the reference numeral 25.

In use, the hook 7 is engaged over the 100

clothes line 4 with the spaced, parallel, side portions of the hook disposed on opposite sides of the enlargement 25 and in this manner the clothes supporting device is retained 5 against sliding movement on the clothes line. The lower portion of the hook is restricted, thus rendering it necessary to spring the bill portion of the hook outwardly when mounting the same on the clothes line or when removing the same from the clothes line. In 10 this manner accidental displacement from the clothes line is prevented.

For securing the clothes to the hanger or support, the jaw 8 is swung forwardly 15 against the tension of the springs 14 by pressing on the plate 23 toward the bar 1 in a manner to swing the tubular sleeve 20 away from the lower end of the bar 1. The clothes are then inserted between the tubular sleeve at 20 the lower end portion of the bar 1 over the free end portion of the clamp 8 after which pressure is removed from the plate 23 and the clothes are securely clamped against the bar 1 in the channel 21. The tubular sleeve 20 25 provides a materially greater area for contact with the clothes than would be had without said sleeve, as will be apparent. The clothes will be suspended over the portions 18 of the clamp and be partially supported thereon, thus providing a snubbing action to prevent tearing of the clothes where clamped by 30 the sleeve 20.

Should it be desired to invert the hanger and suspend the clothes from the hook 7, this 35 may be accomplished by engaging the clothes line 24 in the angles provided by the portions 17 and 18 of the clamp against the adjacent end of the bar 1. In this manner the device is securely mounted on the clothes line in inverted position and the clothes may be inserted in the hooks 7 which will now be in suspended position. The lower portion of the bar 1 is of reduced thickness, as indicated at 26.

45 It is believed that the many advantages of a structure in accordance with this invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

55 A clothes hanger comprising a bar having a beveled end portion, said bar further having a transverse channel in one side thereof and still further having longitudinal grooves extending from the channel over the beveled 60 end portion thereof, the bar still further having a groove extending therearound intermediate the channel and the beveled end portion and intersecting the first named grooves, an integral supporting hook and clothes 65 clamp mounted on the bar and comprising a

length of resilient wire bent upon itself intermediate its ends to provide the hook, said hook comprising spaced, parallel side portions, said wire being further bent to provide parallel angular portions seated in the first 70 named grooves, said angular portions merging with the hook portions at one end, said angular portions merging, at their other ends, with coil springs seated in the transverse channel, securing means engaged with the wire 75 and seated in the second named groove, the clothes clamp comprising leg portions merging with the coil springs, said clamp further including upwardly and forwardly and then upwardly and rearwardly directed end portions said end portions terminating in in-turned portions and a tubular sleeve mounted on the end portions.

In testimony whereof I affix my signature.

ARNOLD R. RASMUSSEN.
